INVENTOR

Victor J. Evans

ATTORNEY

UNITED STATES PATENT OFFICE

EDWARD F. PINK, OF CAMBRIDGE, MARYLAND

WIRE FABRIC

Application filed August 8, 1929. Serial No. 384,333.

This invention relates to improvements in wire fabrics, such as is used for conveyor belts, aprons, screens, and the like, the general object of the invention being to provide a chain at each edge of the fabric which forms a reinforced selvage edge for the fabric which protects the edges and also increases the tensile strength of the fabric.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Fig. 1 is a plan view of a length of fabric constructed in accordance with this invention; and

Fig. 2 is a perspective detail view, showing how the ends of a pair of the wires forming the fabric are connected to a link of the chain.

In these views, the letter A indicates the wire fabric and the letter B indicates a chain connected with each longitudinal edge of the fabric. Each chain is composed of a plurality of links 1, each link being formed of a strip of metal looped upon itself to form an eye 2 at one end thereof, with the limbs 3 having registering openings 4 therein which receive the eye part of the next link.

In carrying out my invention, the ends 6 of a pair of wires 7 of the fabric are passed into the openings 4 of a link, with one wire 40 passing over a top portion of the link and the other under a bottom portion of the link and then the wires are twisted together, as shown at 8, with the twisted portion in the space formed by the openings 4 and with the extremity of the twisted portion extending be-

tween those portions of the link which form the outer wall of the opening 4, as shown at 9. Thus the wires of the fabric are connected with the links of the chains without being soldered, brazed or similarly connected with the links.

This invention not only provides a fabric formed with reinforced selvage edges, but the manner of connecting the ends of the wires with the links prevents the fabric becoming unraveled, and the connection of the wires with the links will not interfere with the flexibility of either the fabric or the chains.

By twisting the ends of the fabric instead of brazing, soldering, or the like, a means of connection is afforded without the necessity of applying heat, which on certain metals destroys the texture and finish and an easy means is afforded to readily disconnect or remove the chain when desired for repair or replacement.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A wire fabric having a chain connected with an edge thereof, the chain consisting of flat links having an eye forming portion at one end thereof, with an opening in its flat portion for receiving the eye portion of another link, each pair of wires of the fabric passing into an opening in a link, with the ends of the wires twisted together within the opening, one wire passing under a portion of the link and the other over a portion of the link.

2. A wire fabric having a chain connected with an edge thereof, the chain consisting of flat links having an eye forming portion at one end thereof, with an opening in its flat

portion for receiving the eye portion of another link, each pair of wires of the fabric passing into an opening in a link, with the ends of the wires twisted together with in the opening, one wire passing under a portion of the link and the other over a portion of the link and the extremities of the twisted portions of the wires extending between those portions of the link which form the outer wall of the opening.

In testimony whereof I affix my signature.
EDW. F. PINK.
